THERMOSTATIC ACCELERATING
PUMP CONTROLLeonard D. Boyce, Kirkwood, Mo., assignor to
Carter Carburetor Company, St. Louis, Mo., a
corporation of Delaware

Application January 10, 1950, Serial No. 137,814

10 Claims. (Cl. 261—34)

1

This invention relates to carburetors for internal combustion engines, and consists particularly in a novel control for accelerating pumps therefor.

Accelerating pumps for carburetors are generally operatively connected to the throttle shaft so that as the throttle is opened the pump discharges a fixed amount of fuel into the mixture conduit, the amount of fuel discharged depending upon the capacity of the pump, length of stroke, and amount of throttle movement. Although the requirements for an accelerating charge diminish as the ambient temperature increases, a conventional pump discharges as much fuel when it is warm as when it is cold.

Accordingly, an object of this invention is to provide an accelerating pump in which the amount of fuel discharged diminishes in proportion to increases in the ambient temperature. I achieve this object by providing thermostatic means for shortening the pump stroke as the ambient temperature increases.

Additional objects and advantages will appear in the specification when read in connection with the accompanying drawings, in which:

Fig. 1 is a plan view of a carburetor incorporating my invention;

Fig. 2 is a partial vertical section of the carburetor of Fig. 1 along the line 2—2;

Fig. 3 is a fragmentary bottom view of the same carburetor;

Fig. 4 is a vertical section view along the line 4—4 of Fig. 1;

Fig. 5 is a fragmentary vertical section view similar to Fig. 4, but showing the pump piston limited to a shortened stroke.

Referring now to the drawings, a downdraft carburetor is generally indicated at 10. Carburetor 10 has a mixture conduit 11, flanged at its lower end as at 13 for attachment to the intake manifold of an internal combustion engine, and a float controlled constant level fuel reservoir 15. Fuel for operation is provided to mixture conduit 11 through orifice 16, and passage 17, extending from reservoir 15 into the central part of web 19 bisecting mixture conduit 11. Additional fuel, for operation at lower manifold suction is admitted to passage 17 through valve 20 and passage 21; valve 20 being urged downward, toward closed position by piston 22, which is drawn downwardly in cylinder 24 by suction, and urged upwardly by calibrated coil spring 26. The outlet of mixture conduit 11 is controlled by throttle valve 27, mounted on shaft 28 which is rotatably journaled in the mixture conduit wall structure.

2

Fuel for idling is provided through restricted tube 29, associated passages (not shown), passage 30 and idle ports 31 discharging into the mixture conduit adjacent throttle 27.

Additional fuel for acceleration is provided by an accelerating pump consisting of cylinder 33 formed in the wall of reservoir 15, inlet check valve 35 communicating with reservoir 15 through passage 36, an outlet passage 38 leading to mixture conduit 11 for discharge thereinto, and piston 39 slidably mounted in cylinder 33. Piston 39 is formed with a stem 41, around which is mounted coil spring 42, the lower end of which bears against plunger 39 and the upper end of which is seated in cup 44 which is slidably mounted on stem 41. Cup 44 abuts against shoulder 45, so that spring 42 urges plunger 39 downwardly in cylinder 33.

Stem 41 is formed with two sets of horizontal downwardly facing shoulders 50, at the stem's upper extremity, and 51 at a somewhat lower position on the stem. Their function will be described in detail below.

For elevating plunger 39, a link 52 having a horizontally extending upper end portion 53 is slidably mounted in vertical guideway 54 formed in the reservoir wall structure and extending above the normal fuel level therein. Stem 41 passes through a horizontal slot in end portion 53 of link 52 so that shoulders 50 are urged downwardly against the upper surface of end portion 53 of link 52, thereby forming a one-way, operative connection between link 52 and stem 41. At its lower end link 52 is adjustably connected by short link 56 to arm 57 rigid with throttle shaft 28, so that as throttle 27 is moved toward open position, link 52 is moved downwardly, thereby permitting spring 42 to force plunger 39 downwardly to discharge fuel from pump cylinder 33. Closing movements of throttle 27 cause link 52 to move upwardly so as to raise plunger 39 and thereby draw a quantity of fuel into cylinder 33 from reservoir 15.

For varying the length of stroke of plunger 39, a device is provided consisting of vertical shaft 58 rotatably journaled in the reservoir wall structure at 60, and having rigidly secured to its upper end a horizontal arm 61. The lower end of shaft 58 extends below the bottom of the fuel reservoir and is bent at a right angle to form a radial arm 58a having at its outer extremity a slotted cylindrical opening 66. The inner end portion of a helical bimetal thermostat 65 fits in slot 63 in rigid post 67 and its outer hooked end slidably fits in slotted cylindrical opening 66 in arm 58a of shaft 58, so that as engine tem-

perature changes, the outer end of thermostat 65 rotates arm 58a and vertical shaft 58. Arm 61 is formed with a vertical channel at its outer end, the width of the channel being equal to the width of the narrowest portion of stem 41, so that the upper surfaces 69, 70, and 71, respectively, of stepped flanges 72 may engage the lower surfaces of shoulders 51 to prevent further downward movement of stem 41 and plunger 39.

When the engine is cold thermostat 65 positions arm 61 so that lowermost steps 69 of flanges 72 are interposed beneath shoulders 51, thus permitting plunger 39 to move its maximum discharge stroke; as the engine temperature increases, medium steps 70 and uppermost steps 71 are successively interposed beneath shoulders 51, thereby reducing the discharge stroke length and consequently the quantity of fuel discharged in proportion to engine temperature.

The invention may be modified in various respects as will occur to those skilled in the art and the exclusive use of all modifications as come within the scope of the appended claims is contemplated.

I claim:

1. In a pump comprising a cylinder and a piston slidably mounted therein, a shouldered stem attached to said piston for imparting axial movement thereto, stepped stop means arranged for variable positioning in the line of movement of said shouldered stem, and thermal responsive means comprising a thermostat operatively connected to said stop means for successively positioning the stepped portions in the line of movement of said shouldered stem.

2. In a pump comprising a cylinder and a piston slidably mounted therein, a shouldered stem attached to said piston for imparting axial movement thereto, a stepped stop member rotatably journaled for variable positioning in the line of movement of said shouldered stem, and thermal responsive means comprising a thermostat operatively connected to said stop member for successively rotating the stepped portions into the line of movement of said shouldered stem.

3. In a pump comprising a cylinder and a piston slidably mounted therein, a shouldered stem attached to said piston for imparting axial movement thereto, a stepped stop member journaled for rotation in a plane normal to the axis of said cylinder and adapted to engage said shouldered stem for varying the axial movement of said piston, and thermal responsive means comprising a thermostat operatively connected to said stop member for successively rotating the stepped portions thereof into the line of movement of said shouldered stem.

4. In a pump comprising a cylinder having inlet and outlet valves, a piston slidably within said cylinder, a shouldered stem attached to said piston for imparting axial intake movement thereto, spring means for imparting discharge movement to said piston, a stop member for limiting the stroke of said piston, said stop member comprising a channel substantially of equal width with the narrow portion of said shouldered stem, the flanges of said channel being formed with a series of steps adapted to abut against the shoulders of said stem for limiting the movement of said stem and piston.

5. In a pump comprising a cylinder having inlet and outlet valves, a piston slidably within said cylinder, a shouldered stem attached to said piston for imparting axial intake movement thereto, spring means for imparting discharge

movement to said piston, a stop member for limiting the stroke of said piston, said stop member comprising an arm pivoted at one end and having at its outer end a channel element substantially of equal width with the narrow portion of said shouldered stem, the flanges of said channel element being formed with a series of steps adapted to abut separately against the shoulders of said stem for limiting the movement of said stem and piston, and thermal responsive means for rotating said stop member.

6. In a pump comprising a cylinder having inlet and outlet valves, a piston slidable within said cylinder, a shouldered stem attached to said piston for imparting axial movement thereto, a moveable stop member for limiting the stroke of said piston, said stop member comprising a channel having its flanges spaced to straddle the narrow portion of said stem, said flanges of said channel being formed with a series of steps adapted to abut against the shoulders upon movement of said stem for limiting the movement of said stem and piston, and thermal responsive means for moving said stop member to position the steps of said shoulders into position for engagement with the shoulder of the stem in accordance with temperature conditions.

7. In a pump comprising a cylinder having inlet and outlet means, a piston slidable within said cylinder, a shouldered stem attached to said piston for imparting axial intake movement thereto, a stop member for limiting the stroke of said piston, said stop member consisting of a rotatable arm journaled at one end and having at its outer end a series of steps arranged parallel to the longitudinal axis of said pump for separate engagement with said shouldered stem, and thermal responsive means associated with said arm for moving said steps successively into position for engagement with said shouldered stem.

8. In a carburetor having a mixture conduit, a throttle valve therein, and a constant level fuel reservoir, an accelerating pump comprising a cylinder formed in the wall of said reservoir, inlet and outlet means connecting said cylinder respectively with said reservoir and said mixture conduit, a piston slidable in said cylinder, a shouldered stem attached to said piston, an operative connection between said stem and said throttle valve, a stepped stop member arranged for variable positioning in the line of movement of said shouldered stem, a rotatable arm supporting said stepped stop member, a shaft rigidly secured to said rotatable arm, said shaft being journaled in a portion of the wall structure of said reservoir extending above the fuel level therein and extending outwardly through the bottom wall of said reservoir, a thermostat secured at one end to the lower extremity of said shaft and fixed at its other end with respect to the bottom wall of said reservoir.

9. In a pump comprising a cylinder and a piston slidably mounted therein, operating means for the piston including a stem, said stem being formed with a downwardly facing shoulder, a stop member formed with a plurality of upwardly facing spaced wall portions arranged for movement into the line of movement of the downwardly facing shoulder, and a thermal responsive means including a thermostat operatively connected to said stop member for successively positioning the upwardly facing spaced wall portions in the line of movement of said downwardly facing shoulder.

10. In a pump comprising a fluid chamber hav-

ing a movable wall, operating means for the movable wall including a stem, said stem being formed with a downwardly facing shoulder, a stop member formed with a plurality of upwardly facing spaced wall portions arranged for movement into the line of movement of the downwardly facing shoulder, and thermal responsive means including a thermostat operatively connected to said stop member for successively positioning the upwardly facing spaced wall portions in the line of movement of said downwardly facing shoulder.
